UNITED STATES PATENT OFFICE

132,053

DESIGN FOR A SLIP OR SIMILAR ARTICLE

Seamon Wolf, New York, N. Y.

Application November 10, 1941, Serial No. 104,096

Term of patent 14 years

To all whom it may concern:

Be it known that I, Seamon Wolf, a citizen of the United States of America, residing in New York city, county of New York, and State of New York, have invented a new, original, and ornamental Design for a Slip or Similar Article, of which the following is a specification, reference being had to the accompanying drawing, forming part thereof, wherein,

The characteristic feature of my design resides in the combination on the specific surplice slip disclosed of the specific embroidered floral edging on the front and back as shown.

I claim:

The ornamental design for a slip or similar article, substantially as shown and described.

SEMON WOLF.
